UNITED STATES PATENT OFFICE.

LUTHER C. CROWELL, OF BROOKLYN, NEW YORK.

SHEET-DELIVERY APPARATUS FOR PRINTING-MACHINES.

SPECIFICATION forming part of Letters Patent No. 276,672, dated May 1, 1883.

Application filed April 30, 1881. (No model.)

To all whom it may concern:

Be it known that I, LUTHER C. CROWELL, a citizen of the United States, residing in the city of Brooklyn, county of Kings, and State of New York, have invented certain new and useful Improvements in Sheet-Delivery Apparatus for Printing-Machines, fully described and represented in the following specification and the accompanying drawings, forming a part of the same.

In said drawings, Figure 1 is a side elevation of so much of a printing-press having the present improvement combined with it as is necessary to show the means for driving the principal mechanisms. Fig. 2 is a plan view, Fig. 3 an end elevation, and Fig. 4 a longitudinal sectional elevation, of the same. Figs. 5, 6, 7, and 8 are sectional elevations, showing the apparatus primarily acting upon the printed sheet in various adjustments; Fig. 9, an elevation of the gear side of a machine embodying my improvements, and showing modifications of some of the mechanisms. Fig. 10 is a plan view, showing more particularly the arrangement of the printing and modified folding mechanisms and the taping of the latter. Fig. 11 is a side elevation taken inside the frame-work to expose some of the principal working mechanisms of the modification. Fig. 12 is a plan view of a part of the mechanisms shown in Fig. 11. Fig. 13 is a side elevation taken inside the frame, and showing a modification of some of the mechanisms and the position thereof in one operative adjustment. Fig. 14 is a plan view of portions of the mechanisms adjusted as shown in Fig. 13. Fig. 15 is a side elevation taken inside the frame, showing these mechanisms in a different position of adjustment. Fig. 16 is a plan view of the same. Fig. 17 is an end elevation, showing particularly the longitudinal folder and one form of transverse folder, the latter being in sectional elevation. Fig. 18 is a sectional elevation of said transverse folder, showing particularly one mode of adjusting its mechanisms. Fig. 19 represents a side elevation, partly in section, showing the primary and secondary apparatus for acting upon the printed sheets. Fig. 20 is a front end elevation of secondary apparatus. Figs. 21 and 22 represent front, end, and side elevations of the secondary apparatus with modified taping.

The improvements embraced in this invention (which in part constitute a division of an application filed by me May 22, 1880) are especially designed to be used in combination with web-perfected printing-machines, which machines, in their present improved state, consist of two principal sets of mechanisms—viz., the printing mechanism and the delivery mechanism. The printing mechanisms of such machines have for many years remained substantially the same, consisting, essentially, of horizontally-arranged printing and impression cylinders capacitated to run at a high rate of speed and to print the opposite sides of a web or long length of material, which printing capacity is alone limited by that of the delivery mechanism, whose function it is to divide the web into short lengths or sheets and deliver the same properly piled. A great variety of delivery mechanisms capable of running at high speed, and thus adapted to be combined with such printing-machines, have been devised, and during more recent periods these delivery mechanisms have been so constructed as not only to deliver the sheets open or flat at high speed, but fold them one or more times during such delivery.

My improvements relate to that class of delivery mechanisms for rotary printing-machines which deliver the sheets in a folded condition.

It is well known to those skilled in the art of printing as carried out in rotary "web-printing machines," in which the web is cut into sheets after it is printed, that the printing-surface covers the circumferential extent of the cylinder, and that therefore any change in the size of the printing-surface can only be made in the direction of the length of the cylinder.

Now, in producing newspapers and similar periodicals, for which the web-printing machine is largely used, the direction in which their first fold should be given depends upon several conditions: first, whether the sheets are printed from columns running around or parallel with the axis of the printing-cylinder; second, whether the sheet be a four-page paper or an eight-page paper; third, also, whether the eight-page sheet be folded intact or composed of two separate four-page sheets. From this it will be seen that the first fold in some

cases should be a longitudinal one and in other cases a transverse one; and my improvements enable one and the same mechanism to fold, first, first longitudinally, the subsequent folds being preferably at a right angle thereto and also to each other, or, second, first transversely, and the subsequent folds at a right angle thereto and to each other. Two sheets may be collected one upon the other, and said collected sheets, or signature, may be folded, first, first longitudinally, the subsequent folds being at a right angle thereto and to each other, or, second, first transversely, the subsequent folds being at a right angle thereto and to each other. If it should be desired that at any time the number or width of columns should be increased or diminished, then the columns must lie parallel with the run of the paper and around the type-cylinder; but if, on the contrary, it should be desired to lengthen or shorten the columns, then they must lie transverse to the run of the paper and parallel with the axis of the type-cylinder.

The same printing-machine may sometimes be required to print a paper from a form the columns of which run around a cylinder, or from a form the columns of which run lengthwise of the cylinder, and it may be desirable in the one case to make the first fold in one direction, and in the other case to make the first fold in the opposite direction.

In this invention, as illustrated and combined with a printing-machine, the first folding mechanism is one that gives the sheets a transverse fold, and the next folding mechanism one that gives the sheets a longitudinal fold; but the transverse folding device is so arranged that it may at pleasure be thrown out of operation and become simply a carrier. Thus the first fold the sheet will receive may be either a transverse or a longitudinal one.

In order to a ready understanding of the invention in all of its details, I will first describe the mechanisms singly.

The printing mechanism shown serves to illustrate the combination of my improvements with a well-known form of such mechanism, said improvements being adapted to any construction of rotary printing mechanism—such, for instance, as that described in Patent No. 212,444, granted February 18, 1879. This mechanism comprises type-cylinders A B and impression-cylinders C D, (see particularly Figs. 13 to 21,) all of which are journaled in a suitable frame-work and geared together by means of toothed wheels, as 101 103 102 104, so as to revolve in unison, one impression-cylinder, as D, being of large diameter, to operate as a set-off cylinder, as is common. The type-cylinders A B may be of a diameter equal to two lengths of the product to be printed twice that size, or any multiple thereof, as may be desired, and be of a length to print one or more products side by side, as is common, if desired. For the purpose of this specification I have shown the impression-cylinder B of one size in Figs. 9 and 11 and of double that size in Figs.

13 and 15. The usual blanketing of the impression-cylinders and the common fittings of the type-cylinders, whereby they are adapted to hold forms of type or plates, will be used and any suitable inking apparatus.

The primary folding mechanism, or that one which is capacitated to fold the paper transverse to its direction of travel, consists of a rotating carrier, E, (preferably a cylinder,) the periphery or shell of which is perforated to accommodate the protrusion of the various mechanisms it carries, the shaft 51 of which is journaled in the frame-work and provided with a driving toothed wheel, 105, meshing with the wheel 104, whereby said carrier is caused to rotate with the same surface-speed as that of the printing mechanism, though in Figs. 1 to 8 the connecting-gearing is marked 105 106 102.

The construction of the primary folding mechanism, which will preferably be used in practice because of the simplicity and compactness of its parts, is shown in Figs. 1 to 8, and will now be particularly described. Its carrier E is provided at one point of its periphery with a folding-blade, 9, mounted to turn with a shaft, 31, that is journaled in the carrier-heads, said shaft supporting oppositely-extended folding-blades, constituting a double folding-blade, such as is described in Patent No. 171,196, granted December 14, 1875. Said double folding-blade is, moreover, modified from the structure described in said patent, so that one of its members or blades may be readily removed and replaced by any common means, or by that described in Patent No. 214,066, granted April 8, 1879. Its shaft 31 is extended through one head of the carrier and provided with two opposed rock-arms, 10, one of which, during each revolution of the carrier E, engages a guide-way or cam-path formed by a flying cam, 12, and a stationary cam, 13, that is fast to the frame-work. This flying cam 12 is mounted upon the face of a toothed wheel, 45, that is carried by a short stud journaled in the frame-work. (See Fig. 2.) This wheel, and consequently the cam, is rotated in proper time by means of a toothed wheel or driving-pinion, 46, fast upon the shaft 51 of the carrier E, said flying cam being thereby rotated so as to cooperate with the stationary cam in directing the rock-arm of the folding-blade through a cam-groove that will cause the blade-shaft to make a semi-rotation, and one blade to be thereby protruded from and withdrawn into the carrier, during which movement it enters the space between the rollers 32 33 and accomplishes the folding operation, all of which is particularly described in said Patent No. 171,196, from which description and that of Patent No. 214,066 it will be understood that although the blade-shaft makes a semi-rotation at each revolution of the carrier E, such rotation becomes an idle or inoperative one when one blade is removed or the folder has a single folding-blade. At a point opposite to that in which the folding-blade is mounted the carrier E is provided with a shaft,

cases should be a longitudinal one and in other cases a transverse one; and my improvements enable one and the same mechanism to fold, first, first longitudinally, the subsequent folds being preferably at a right angle thereto and also to each other, or, second, first transversely, and the subsequent folds at a right angle thereto and to each other. Two sheets may be collected one upon the other, and said 10 collected sheets, or signature, may be folded, first, first longitudinally, the subsequent folds being at a right angle thereto and to each other, or, second, first transversely, the subsequent folds being at a right angle thereto and to each other. 15 If it should be desired that at any time the number or width of columns should be increased or diminished, then the columns must lie parallel with the run of the paper and around the type-cylinder; but if, 20 on the contrary, it should be desired to lengthen or shorten the columns, then they must lie transverse to the run of the paper and parallel with the axis of the type-cylinder.

The same printing-machine may sometimes 25 be required to print a paper from a form the columns of which run around a cylinder, or from a form the columns of which run lengthwise of the cylinder, and it may be desirable in the one case to make the first fold in one 30 direction, and in the other case to make the first fold in the opposite direction.

In this invention, as illustrated and combined with a printing-machine, the first folding mechanism is one that gives the sheets a transverse fold, and the next folding mechanism one that gives the sheets a longitudinal fold; but the transverse folding device is so arranged that it may at pleasure be thrown out of operation and become simply a carrier. 40 Thus the first fold the sheet will receive may be either a transverse or a longitudinal one.

In order to a ready understanding of the invention in all of its details, I will first describe the mechanisms singly.

45 The printing mechanism shown serves to illustrate the combination of my improvements with a well-known form of such mechanism, said improvements being adapted to any construction of rotary printing mechanism—such, 50 for instance, as that described in Patent No. 212,444, granted February 18, 1879. This mechanism comprises type-cylinders A B and impression-cylinders C D, (see particularly Figs. 13 to 21,) all of which are journaled in a suitable frame-work and geared together by means of toothed wheels, as 101 103 102 104, so as to revolve in unison, one impression-cylinder, as D, being of large diameter, to operate as a set-off cylinder, as is common. The type-cylinders A B may be of a diameter equal to two lengths of the product to be printed twice that size, or any multiple thereof, as may be desired, and be of a length to print one or more products side by side, as is common, if desired.

65 For the purpose of this specification I have shown the impression-cylinder B of one size in Figs. 9 and 11 and of double that size in Figs.

13 and 15. The usual blanketing of the impression-cylinders and the common fittings of the type-cylinders, whereby they are adapted to hold forms of type or plates, will be used and any suitable inking apparatus.

The primary folding mechanism, or that one which is capacitated to fold the paper transverse to its direction of travel, consists of a rotating carrier, E, (preferably a cylinder,) the periphery or shell of which is perforated to accommodate the protrusion of the various mechanisms it carries, the shaft 51 of which is journaled in the frame-work and provided with a 75 driving toothed wheel, 105, meshing with the wheel 104, whereby said carrier is caused to rotate with the same surface-speed as that of the printing mechanism, though in Figs. 1 to 8 the connecting-gearing is marked 105 106 102. 85

The construction of the primary folding mechanism, which will preferably be used in practice because of the simplicity and compactness of its parts, is shown in Figs. 1 to 8, and will now be particularly described. Its carrier E is provided at one point of its periphery with a folding-blade, 9, mounted to turn with a shaft, 31, that is journaled in the carrier-heads, said shaft supporting oppositely-extended folding-blades, constituting a double folding-blade, such as is 9 described in Patent No. 171,196, granted December 14, 1875. Said double folding-blade is, moreover, modified from the structure described in said patent, so that one of its members or blades may be readily removed and replaced by any common means, or by that described in Patent No. 214,066, granted April 8, 1879. Its shaft 31 is extended through one head of the carrier and provided with two opposed rock-arms, 10, one of which, during each 10 revolution of the carrier E, engages a guide-way or cam-path formed by a flying cam, 12, and a stationary cam, 13, that is fast to the frame-work. This flying cam 12 is mounted upon the face of a toothed wheel, 45, that is carried by a short stud journaled in the frame-work. (See Fig. 2.) This wheel, and consequently the cam, is rotated in proper time by means of a toothed wheel or driving-pinion, 46, fast upon the shaft 51 of the carrier E, said flying cam being thereby rotated so as to co-operate with the stationary cam in directing the rock-arm of the folding-blade through a cam-groove that will cause the blade-shaft to make a semi-rotation, and one blade to 12 be thereby protruded from and withdrawn into the carrier, during which movement it enters the space between the rollers 32 33 and, accomplishes the folding operation, all of which is particularly described in said Patent 12 No. 171,196, from which description and that of Patent No. 214,066 it will be understood that although the blade-shaft makes a semi-rotation at each revolution of the carrier E, such rotation becomes an idle or inoperative 130 one when one blade is removed or the folder has a single folding-blade. At a point opposite to that in which the folding-blade is mounted the carrier E is provided with a shaft,

ation, although the gear-wheel 60 carries two cams, 1 and 2, it is apparent that the wheel 60 or the cam 1 might be secured in a fixed position, so that one cam would cause the movement of the fingers each time that they pass the rollers 32 33. In consequence of the other operations carried on by this mechanism, in which it is necessary that the fingers 5 be operated at only every second revolution of the cam E, the actuating-cams 1 2 are secured to the wheel 60, which is twice the size of its driver, said driver being a tooth-wheel, 59, secured to the shaft of carrier E. Therefore the carrier E will make two revolutions while the wheel 60 makes but one, thus presenting the same cam, as 1, in acting position at every alternate revolution of the carrier E.

If, now, it be desired to change the arrangement of the printing-plates carried by the type-cylinders and so place them that each sheet printed thereby will be the component half of a complete product, in which case it would be desirable to bring two successive sheets one upon the other, or if, for any other reason, it is desirable to collect two sheets one upon the other, it is but necessary to remove one of the cams, as 2, from the wheel 60, when the apparatus will operate as follows: When the first of this pair of sheets, whose forward end is carried by the pins 6, approaches the point occupied by the rollers 32 33, that side of the wheel 60 whence cam 2 was removed is then presented toward said rollers, and consequently permits the rock-arm of the fingers to pass that point without being moved. The pins consequently retain their hold upon said sheet and carry it forward in the relative movement of the carrier E. It thus carries the first sheet entirely around with the carrier, and causes the same to receive the second sheet upon it, the two then being impaled on the pins 6, and the cutting instrumentalities of the carriers E and F severing this second sheet in like manner as it did the first. When the forward edges of these combined sheets held by the pins 6 approach the rollers 32 33 the wheel 60 will then have made the last half of its revolution, and will present its cam 1 in proper position to engage the rock-arm 11 of the fingers 5 and vibrate the same outwardly, thereby stripping the ends of the two combined sheets from the pins and entering them simultaneously into the bite of the rollers 32 33, from whence the sheets will pass out for subsequent treatment, as before described.

Although from this description it will appear that the carrier E, when provided with pins and mechanisms governing the control of the paper, together with the conductors 48, constitute a gathering or controlling mechanism, such a gathering mechanism is not herein claimed as novel, the same forming the subject-matter of another application.

If, now, it is desired to fold the sheets transversely, either singly or in gathered pairs, the same may be accomplished by bringing into action the folding-blade 9, which may be done

by simply restoring its flying or actuating cam 12 into its operative position, as shown in Figs. 1 and 2, the conductors 48 then being raised out of action, and the position of the cam-wheel 60 (now provided with both its cams 12) will be changed to that shown in Figs. 7 and 8, its carrying-stud being secured to the frame in the hole shown by dotted lines in Fig. 2, 75 where it will rotate, as before described: In this arrangement of the parts the cams 1 and 2 upon the wheel 60 will so operate that at each revolution of the carrier E the fingers 5 will be vibrated outwardly to release the end of the sheet in passing the point nearly opposite to the rollers 32 33, thus carrying each sheet onward far enough to present its middle portion, or that part which is to receive the fold, properly before said rollers, as will be understood from said Patent No. 171,196. The folding-blade will make a semi-revolution at each rotation of the carrier E, and one of its blades 9 be protruded between the rollers 32 33 at each rotation of said carrier. It will therefore be understood that each sheet engaged by the pins will be carried past the rollers 32 33 and be folded by the operation of the folding-blade into the nip of said rollers, the fingers being vibrated at the proper time 95 to release the forward end of said sheet to enable it to pass between the rollers 32 33 in a once-folded condition, which fold will be transverse to the run of the web, and each folded sheet may then be delivered by the tapes shown 10 for subsequent operations.

If it is desired to collect two sheets one upon the other and to fold the same simultaneously with a transverse fold, one cam, as 1, is removed from the cam-wheel 60 and one blade 9 from the folding-blade, as is shown in Fig. 8. The first sheet will be carried by the pins around with the carrier E, the cam-wheel 60 then so rotating as to admit the rock-arm of said fingers to pass by it without being acted upon and the folding-blade shaft making that half of its revolution which turns the single blade 9, it then carries inwardly as the rollers 32 33 are passed. The second sheet is received upon the first, as heretofore explained with reference to Fig. 6, the web is severed, and the two sheets impaled upon the pins 6 are carried onward past the rollers 32 33, and when the middle portion or folding-point of such collected sheets arrives before said rollers, that revolution of the folding-blade shaft is made which protrudes the single folding-blade outwardly, whereby the two sheets are simultaneously doubled into the nip of the rollers 32 33, the wheel 60 simultaneously bringing into operation its cam 2, and causing the vibration of the fingers to release the leading ends of the two sheets, so that the said sheets may be free to pass through the rollers 32 33, from whence they may be delivered for subsequent manipulation. It will also be understood that when it is desired the pins 6 may be turned inwardly and rendered inoperative, and also that the projection on carrier F may be re-

moved when the cylinders E F would be empty carriers.

A modified construction of devices for effecting these same operations is shown in the primary apparatus, more particularly by Figs. 9 to 20, which will now be explained. In this arrangement the carrier E is provided with a single folding-blade, 9, that projects from the shaft 31, which shaft is now adapted to be vibrated, so as to swing the folding-blade, such movement being imparted by a single rock-arm, 10, whereby said blade is protruded at proper times beyond the periphery of the carrier for coaction with the rollers 32 33, which are here shown in form of pulleys and as provided with pinions 61 62, whereby they are driven by the pinion 61 from the wheel 105. The longitudinal row of pins 6 is arranged to be automatically protruded beyond and drawn within the periphery of the carrier, or to be fixed in either their protruded or withdrawn positions. For this purpose they may be secured to a plate or bar, 34, as in Fig. 11, arranged to slide in ways provided within the carrier, which plate or bar is provided with a rack or racks, with which a pinion or pinions, 35, fixed upon a shaft, which may be the shaft 30, engage. In this structure a spring, as 48, or a spiral spring, will be arranged to so rock the shaft 30 as to cause it to protrude the pins, its rock-arm 11 being actuated to cause the pins to withdraw at proper times by a cam mechanism equivalent in its function and operation to the cams carried by the cam-wheel 60. The carrier E is further provided at a point opposite to the pins 6 with another set of pins, as 17, (see Figs. 13 and 15,) that are curved to project from a rock-shaft, 93, journaled in the carrier-heads, which shaft has at one end a rock-arm, 43, that may be moved into a position to protrude the pins through apertures in the blade 9, or withdraw the same within the carrier. These pins may be secured in either of such positions by means of spring-seated pins, as 38, projecting through a hole in the carrier-head and engaging a hole in said rock-arm 43. (See detached view, Fig. 17.) The pins 6 may be maintained in their withdrawn or protruded position by like means, and both or either sets of these pins may be secured in either of their positions by any other means. This carrier E is furthermore provided at points near the projecting points of the pins 6 and that of the blade 9 with longitudinal cutting-grooves 7 and 12, which will preferably be provided with cutting-blades; or one wall of the groove 12 may be formed by the edge of the shell of the carrier and the other wall by the edge of the blade 9, with which cutting-blades 28 and 29, supported by the carrier F, co-operate. The cutting-blade 28 is arranged so that it may be removed bodily from the carrier, in manner similar to that described in the Patent No. 180,966, August 8, 1876, which blade, when in place, however, co-operates during each turn of the carrier with the cutting slot or blade 7. This removability

renders it convenient to provide the carrier F with a blade having a cutting-edge that will make a complete severance, or with one having portions of its cutting-edge removed. The cutting-blade 29 has portions of its edge removed, and is arranged to be carried constantly by the carrier, but constructed so as to be thrown into or out of action, as may be required. Thus it is mounted so as to slide in ways provided within the carrier, and has one or more racks that are engaged by a pinion or pinions, 39, (see Fig. 15,) fast upon a shaft journaled in the heads of the carrier, and provided at one end with a rock-arm, 40, by the movements of which said rock-arm this cutting-blade may be protruded from or withdrawn within the periphery of said carrier, as may be required. It may be secured in either of these positions by means of a pin or screw passed through a hole in the rock-arm and entered into holes, as 41, in the carrier-head, or it may be arranged to be secured in manner similar to that shown and described for securing the pins of the carrier E. Its two positions are shown in Figs. 11 and 13. Any other cutting mechanism may, however, be used, and all of the cutting instrumentalities should be constructed so that they may be removed or rendered inoperative, and thus convert the carriers E and F into simple conducting rolls or cylinders.

The mechanisms for controlling the action of the devices supported by the carrier E are as follows: A tripping lever bar, 50, which is branched to properly support tripping-dogs 22 23, is arranged so as to be capable of longitudinal or sliding movement, being for this purpose provided with an elongated guide-slot, 25, whereby it may move on a guide-pin, 26, projecting from the frame-work, and be guided by its forked end, that embraces a shaft which carries an adjustable cam, 99, in the path 19 of which a stud or roller, 20, projecting from the bar 50, enters. This bar 50 is furthermore provided with means for securing it in stationary forward or rearward positions, the same being in one construction (see Figs. 11 and 12) a screw, 69, tapped through the frame and adapted to be entered into one of the holes 70 71, with which the bar is provided, and in another construction the cam 99 is made the means for securing the proper adjustment, as will presently appear. This cam may be mounted to revolve upon the shaft 100 of the cylinder D, or upon a short shaft, 80, projecting from the frame-work. In the latter case its appropriate timely rotation is produced by means of a toothed wheel, 107, fast on the shaft 100, which engages a pinion, 63, turning freely on said short shaft 80, to which wheel the cam is secured. This cam may be adjusted so as to turn operatively, and thus reciprocate the bar 50, as in Figs. 11 and 12, where its movement is shown to be accomplished by means of the grooved sleeve 3 of the cam carrying pinion 63, which grooved sleeve is embraced by the arms of a bifurcated shipping-plate, 36, that is moved by

an adjusting-screw, 37, to carry said cam and pinion laterally, whereby the stud 20, carried by the bar 50, may be entered into or withdrawn from the groove in the cam and the movements of the bar be accomplished or suspended. In Figs. 13 to 15 the cam is arranged to be secured to the shaft 100, so as to revolve therewith, by means of a screw, 81, that is tapped through the hub of the cam and enters the said shaft. It may be secured to the side frame and thus held stationary by withdrawing the screw 81 and so turning a screw, 82, tapped through the side frame, that its end will enter a suitable one of the holes, 91, provided in the side of the cam. When the bar 50 is in its forward position its dog 22 will be held so that it will intercept the rock-arm 11, and thereby cause the pins 6 to be drawn within the periphery of the carrier E, thus disengaging them from the paper which is impaled by them, and the dog 23 will be held in position to intercept the rock-arm 10 of the blade 9 and cause the shaft 31 to be vibrated and swing said blade 9 outward and into the space between the rollers 32 33, as in Fig. 15. If it is desired to hold the rear end of a severed sheet or sheets carried by the cylinder E when the same is operating to collect sheets, the forward ends of which sheet or sheets are held as before described, a set of pins, as 57, (see Figs. 5 to 8,) located in front of the cutting member of said cylinder, would, when the sheet is severed, penetrate and hold the same until they are stripped therefrom by the action of the rollers 32 33.

The operation of these modified structures of the primary apparatus is as follows: If it is desired that each sheet produced by the severing of the web into short lengths through the operation of one or of both sets of cutting devices with which the carriers E and F are provided, which in the one case will be, say, whole sheets, and in the other half-sheets, it is only necessary to adjust the cam 99 by either of the described means so that it will hold the tripping-bar 50 in its rearmost position and stationary. This will remove the dogs 22 23 so far rearwardly that they will not cause any of the devices supported by the carrier E to become active. In delivering whole sheets flat, said sheets being only partially severed from the web by the action of the cutter 28, which has removed portions, the sheets, in the form of a web partially connected at its lines of ultimate division into sheets, is simply led from the cylinder D, passed between the carriers E and F, and entered into the nip of the rollers 32 33. If it is desired that these sheets shall be entirely severed from the web, the forms may be set back in the type-cylinders, the cutting-blade 28 removed, and the cutting-blade 29 thrown into action. The bar 50 will then be adjusted in its forward position, and the pins 6 be adjusted in their withdrawn or inward position, which removes their rock-arm 11 out of the path of travel occupied by the dog 22. The head of each sheet will then be impaled upon the pins 17, and, as it is passing

the point occupied by the roller or pulley 32, the rock-arm of the blade 9 will engage the dog 23 and cause said blade to swing outward to direct the leading end of said sheet into the nip of the rollers 32 33, as in Fig. 15. If it is desired to deliver half-sheets flat, both cutters 28 29 will be brought into operation, the bar 50 will be adjusted so as to render the blade 9 inoperative, and both sets of pins in the carrier E will be fixed in their withdrawn position, and both knives 28 29 have cut-away portions. Each half-sheet will then be partially severed from the web and pass between carriers E F and the rollers 32 33. If both cutters 28 29 operate to entirely sever the web, it will be necessary, in order to carry the half-sheets then produced into the nip of the rollers 32 33, to provide the roller 32 with pins or hooks 95, which may be caused by proper devices to operate so as to enter the leading end of each sheet, strip it from the carrier E, and, having entered the same into the nip of rollers 32 33, be withdrawn. If it is desired to collect or associate two whole sheets one upon the other and deliver the same simultaneously through the rollers or pulleys 32 33, the cam 99, actuating the bar 50, will be put into operation, so as to cause said bar to make a forward reciprocation at each second revolution of the carrier E. This will present the dog 23 in position to operate upon the rock-arm 10 and move the swinging blade 9. The blade 28 being removed, the pins 6 secured in their withdrawn position, and the blade 29 thrown into action, the head of the first sheet will be impaled upon the pins 17, and will be carried around with the carrier E, receive the second sheet upon it, the blade 29 cutting the web into sheets, which sheets will, when their leading ends arrive at the roller 32, be simultaneously stripped from the pins 17 by the action of the blade 9, which at this time is operated by the contact of its rock-arm 10 with the dog 23, which is moved forward in proper position for this purpose, the time being that of the forward movement of the bar 50. In this operation, of course, the pins 95 will be out of action. If, now, it is desired to deliver each full sheet with a transverse fold, the pins 17 are thrown out of action, the pins 6 are thrown into action, and the blade 28 is thrown into action, and the bar 50 is adjusted in its forward position, so that its dog 22 will operate the pins 6 and its dog 23 will operate the folding-blade 9 at each revolution of the carrier E. Each sheet impaled upon the pins 6 will be carried by them around to a point opposite the rollers 32 33, at which time the dog 22 will operate to withdraw the pins from the end of the sheet, and the dog 23 will operate to swing the folding-blade 9 outward between the rollers 32 33, thus carrying the sheet with it and doubling it into the nip of the rollers 32 33, thereby accomplishing its folding upon a line transverse to the direction of its travel. As this sheet is passing between the rollers 32 33 and the web between the carriers E and F the cutter 28 operates to sever the sheet un-

dergoing the folding operation and leave the end of the web which is to form the succeeding sheet impaled upon the pins 6. By a slight modification of the form of the bar 50 and its cam and the provision of additional folding-blades, half-sheets might be folded in a similar manner.

In the folding operation the blade 9 is prevented from dragging over the periphery of the roller 33, or the paper thereon, in making its retiring movement, by a guard of common form, against which the arm 10 of the folding-blade 9 presses, and as soon as clear therefrom is quickly redirected by the action of the spring to its former position in the carrier, the dog 23 simultaneously making its retiring movement.

The sheets, either extended flat or folded transversely, may be directed from the rollers 32 33 to any form of apparatus, either for further folding the same or for piling them, as is described in said Patent No. 171,196, or be manipulated by any structure of longitudinal folder composed of turners.

The secondary sheet-manipulating apparatus, as illustrated herein, consists of a structure which embodies an internal guide and external turners, by the coaction of which a sheet or web of paper drawn over said guide and through the turners has its sides brought together or lapped, so as to impart to the web or sheet the desired longitudinal fold. The web or sheet, as it enters upon this guide, is extended flat widthwise, and its sides are gradually turned or deflected toward each other, and are finally brought together in passing between said turners. This secondary or longitudinal folding mechanism consists of an internal supporting or turning guide, G, preferably formed by bending the forward portion of the main body of a rectangular metal plate, (of a width equal at least to that of the fabric designed to be folded,) so that the forward edges of its centrally-bent sides 14 18 shall be united or lie together in a straight line. Such a structure provides bends or internal turners, 15 16, extending rearward from the point t, where the sides unite with the body and flare outward toward the rear end of said body.

The external guides or turners, 55 56, which may be rollers, pulleys, or fixed surfaces supported in spring-seated bearings, to permit either single or double sheets to pass between, are arranged so that their inner surfaces stand parallel with the meeting edges of the side plates of the guide G, and so as to provide between their inner faces a sufficient space for the passage of the lapped side sections of the web or sheet, which are brought together in passing between said turners. The rear edge of the guide G will be straight, and may be turned over or secured to a bar, 21, by which the guide will be attached to the supporting-frame, or be extended rearwardly and be connected with the shaft of the roller or pulleys 32. The external turners, 55 56, when made in the pulley or roller form, will preferably be

geared together and properly driven to act as drawing-rollers to draw the web or sheet through the folder. As the meeting forward edges of the inwardly-bent sides of the plate forming the internal guide stand at right angles to the bottom edges of the sides of said plate, and the rear edge of the plate is straight in a transverse line, such disposition will cause the central surface of the plate to stand at an angle of about forty-five degrees with respect to said meeting edges, and the lines of union between the inwardly-bent sides or plates 14 18 and the central surface or main body of the plate, which lines constitute the bends or internal turners, 15 16, will stand at an obtuse angle with respect to each other. Hence, as the distance transversely upon any line drawn parallel with the said meeting forward edges from one edge of the side 14 over the plate and to the edge of the side 18 must be the same and equal to the length of the rear or straight edge of the plate, it follows that a sheet or web held in contact with said plates, and thus lapped or folded longitudinally, will be properly distended widthwise; and as the internal guide is in this case continuous from the point where the fabric passes over its rear edge through the plates 14 18, it also follows that the side sections, which are turned or deflected centrally to lap upon each other, have their margins supported until the same leave the front edges of said plates, when the folding is completed, and hence that the web at said point of its being so lapped or folded has no slack portion, whereby its perfect manipulation would be impaired or rupture of its body result. It will therefore be apparent that, while the meeting forward edges of the sides 14 18 are kept at a right angle to the folding-line or point of union between the lapped sides of the fabric, the internal guide may be bent so that its rear edge will be brought nearer to the lower ends of the meeting forward edges of said plate, and that the more it so approaches said forward edge the greater will be the acuteness of the angle of the plate with respect to its meeting forward edges, which may continue until the two stand nearly in the same plane or parallel with each other, the angle which the bends or turners 15 16 bear to each other in like manner growing more obtuse. The raising contra bending of the plate will of course produce the opposite effect. These angles of retraction will also vary according to the length given rearwardly to the plate, and will likewise be changed if the lines of union between the sides 14 18 and the central surface of the body of the plate, constituting the bends or turners 15 16, be rounded instead of abrupt. In all cases, however, the same extent of bearing-surface widthwise for the fabric will exist upon any transverse line drawn from one edge to the other of the side plates and parallel with the meeting edges of the forward end of the plate, and the fabric will therefore be perfectly sustained in such modified forms.

It will be apparent from the foregoing de-

scription that the internal parts of the folder may be divided transversely into a number of narrow plates, so long as a sufficient number of bearing-surfaces be provided to sustain the fabric, especially its margins, and prevent it from sagging inward or otherwise becoming distorted from a true course, whereby its perfect folding would be prevented. The internal guide may likewise be composed of a series of narrow plates or rods or wires, that start from the bar 21 and extend forward at the proper angles in lines coinciding with the path of travel of the sheet or web until they terminate at the perpendicular line of the triangular form they will thus constitute. So, too, the bar 21, or an equivalent widthwise support, being provided for the turners 15 16, may be contracted to any extent so long as the fold-forming point *t* is maintained, and in all cases either one of the external turners will be sufficient, provided a means for drawing the sheet through the longitudinal folder is provided. Such constructions of the longitudinal turner are within the present invention, and will operate to perfectly support the fabric and cause its side sections to be brought together to form the longitudinal fold. Assuming the tapes, which this longitudinal folder is shown as provided with in the drawings, to be dispensed with, the operation will be as follows: The web, either in the form of a continuous fabric, or one having lines of transverse division partially severed in it, but maintaining its character of a continuous web, will pass directly from the printing mechanisms between the carriers E and F, whose mechanisms then are non-operative, and, carried between the rollers or pulleys 32 33, will enter upon this longitudinal folder and be distended in the same plane to its fullest width and flat in passing onto the rear edge of the guide G or over its bar 21. In passing over the body of the guide G its side sections will be directed over the turners 15 16 and droop against the side plates, 14 18, of said guide, the sides of said web being thus gradually brought together, and their leading edges will be lapped so as to meet and enter between the external turners, 55 56. In this disposition of the web it will be so disposed as to be folded upon a longitudinal line, the doubling or folding of which is at the point *t*. An onward motion being imparted to the web, its longitudinal folding will be accomplished by the direction given it in passing through this longitudinal folder. Thus, as the web runs in the same direction as the internal guide is disposed, and the latter is a continuous plate or former, it follows that the web will be supported longitudinally and transversely, not only during its movement over the internal guide, G, while undergoing the folding operation, which supporting is especially desirable, as it permits the side sections to be positively supported while the material is being deflected from a common plane, or in passing over the internal guides or turners, 15 16, but at the point where the sides

of the web come within the control of the external turners, 55 56, by which construction of the parts the perfect run of the web will be accomplished and its longitudinal folding performed without danger of rupture, buckling, or other injury from distortion.

The side plates, 14 18, may be omitted, if desired, and the greater part of the body-plate 75 of the external guide may also be removed, the turners 15 16 and 55 56, in connection with the bar 21 or a guiding-roller, as 32, being sufficient to perform the longitudinal folding, when, as in this case, the web is continuous. 8 Although I have described this longitudinal folder as operating upon a web or continuous sheet for convenience of setting forth its operation, it is designed to have combined with it a means for severing the web into short lengths 85 or sheets. This may be done by a cutting mechanism operating to divide the web transversely, and located so as to perform that operation either before the longitudinal folding is accomplished, as by the cutting devices of 90 the carriers E F, or be arranged to sever the web after it has received its longitudinal fold, as by the devices of the carriers H I, yet to be described; but where the cutting devices of the carriers E F operate to partially sever a 95 web, such a web, when longitudinally folded, may be divided into sheets by the action of the carriers H I, when the latter are made to travel slightly faster than the printing mechanisms, and thus break the web upon its partially-divided lines as the tail of each sheet emerges from between the turners or rollers 55 56 in the manner common in web-printing machines, the principle of which is explained in the Patent No. 192,914, granted July 10, 105 1877. When, however, the web is to be divided by transverse severance that forms it into short lengths or sheets through the instrumentality of the cutting device provided in the carriers E F, the longitudinal folding apparatus will require to be provided with a means for conducting the leading edge of each sheet through it, and, as it is obvious from the flexible character of the paper that such conducting means should be a moving device, tapes are here provided to carry the sheets smoothly through said longitudinal folder. One set of tapes for this purpose (illustrated more particularly by Figs. 9 to 11, 13, 15, 19, and 20) will now be described. As shown, four sets of endless outside tapes are employed, two of which endless tapes, *a c*, are arranged to pass over the "former" G near the point traveled by the margins of the sheets or material, while the remaining two endless tapes, *i o*, are centrally arranged. The margin-tapes *a e* run from the pulley or roller 33. Thence they pass onto the base or rear surface of the guide G, follow near its margin edges, pass over the bends or turners 15 16, follow near the margin edges of the side plates, 14 18, and return around pulleys or the inner ends of the rollers 55 56, the tapes *a* returning over the inner ends of a roller, 88, and a roller, 84, or bending-pul-

leys substituted therefor, and a bending-pulley, 85, to the pulley or roller 33, while the tape *o* returns in like manner to the said roller or pulley over the inner end of a roller, 90, and a roller, 86, or bending-pulleys substituted therefor, and a bending-pulley, 87. The central tapes, *i o*, run from the roller or pulley 33, thence pass onto the base or rear surface of the guide G, follow near its central line, pass over the bends or turners 15 16 near the folding-point *t*, and return over the ends of the outer rollers, 55 56, or pulleys substituted therefor, the tape *i* thence passing rearwardly over the outer end of the roller 88 and the roller 84, or a pulley substituted therefor, thence over the bending-pulley 89 to the roller or pulley 33, while the tape *o* returns rearwardly over the outer end of the roller 90 and the roller 86, or pulleys substituted therefor, and a bending-pulley, 91. The central tapes may be omitted entirely, though it is preferable to retain at least one—say the tape *i*—as is shown in Figs. 17, 21, 22. It will run from the roller 33, or a pulley substituted therefor, passing onto the central portion of the former G, and extending quite near its folding-point *t*, where it returns over a bending-pulley to the roller or pulley 33. A set or sets of under tapes might of course be arranged to coact with these upper tapes; but the same are unnecessary, especially when the continuous or plate form of folder is used. Where the material operated upon by the longitudinal folder is in the form of a web a single central tape may be used, and will serve to carry the leading edge of the web through the apparatus. By this structure of longitudinal folder and its combination with rotating printing mechanisms, the two will coact, so that a freshly printed web of paper led directly from the printing mechanisms to this longitudinal folder can be folded parallel with the run of the web or sheets composing the same, and such folding will be accomplished without separating the sheets any distance apart or providing a time space between them for the operation of the longitudinal folding mechanism, and this is also the case whether the web be severed by transverse cuts that divide it into short lengths or sheets performed before the longitudinal folding is effected or after the same is effected. By this construction the printing mechanisms may run at the highest possible speed attainable, according to the condition or strength of the material printed upon, which alone can limit their speed, for the reason that since there is no separation of the sheets or distance provided between succeeding ones, and this longitudinal folder is capable of performing its function as rapidly as the material can be passed through it, there can be no limit to the highest rate of speed except the weakness of the material acted upon. It is desirable to further fold the product emerging from the rollers or turners 55 56, which product may be, first, a full sheet folded longitudinally; second, two full sheets associated together and folded longitudinally;

third, a full sheet folded transversely and longitudinally; fourth, two full sheets associated together and folded transversely and longitudinally; fifth, a half-sheet folded longitudinally. If a slitter, as 133, as shown in Figs. 13 and 15, is mounted, so as to bear on the paper, upon the internal guide, G, near its folding-point *t*, said slitter will operate to divide the web or sheet in its longitudinal center, so that the product emerging from the rollers or turners 55 56 in any of the above forms will be divided longitudinally, and in the case of full sheets will be tantamount to gathering two sheets printed side by side by a lateral transference. It will thus appear that the size of the product emerging from the rollers or turners 55 56 may in length be equal to the length of a full sheet or that of a half-sheet. Consequently the carriers H I are provided with folding devices, which are arranged to operate upon both sizes of product, which, for convenience, we will call "full sheets" and "half-sheets," and as it is further apparent that when the cutting is to be performed by the carriers H and I, as in case the web emerges from the turners 55 56, having been transversely severed into short lengths, it will furthermore be necessary to provide the carriers H I with proper cutting devices to sever such web into half-sheets or whole sheets. The folding mechanism operating upon the sheets at this point may be of any of the well-known constructions, whether rotary in operation or constructed of turners, as herein described. As here shown, the rotary folding mechanisms supported by the carriers H I are shown as well adapted for completing the folding desired. These carriers are geared together by toothed wheels 109 110, (see Fig. 10,) and will be driven in unison with the other mechanisms by means of a bevel-wheel, 64, on the shaft of the carrier H, which wheel is engaged by a similar wheel, 65, on a cross-shaft, 66, that carries a toothed wheel, 111, which, through an intermediate, 112, is geared to and driven by the wheel 106 on the shaft of the carrier F. I will now describe the mechanisms with which these carriers are provided, and then explain their operation. The carrier H (see Fig. 18) is provided with four sockets at equidistant points in its periphery, in which the removable blocks supporting the tucking or creasing blades 97 98, and other blocks carrying cutting-blades 76 76 and sheet-carrying pins 53 54, may be adjusted or removed. The carrier I is provided with sheet-seizing jaws, the vibrating members 72 73 of which are upon rock-shafts and actuated by a cam-movement in any common manner, substantially as is explained in said Patent No. 143,674, October 14, 1873. The jaw 73, however, is here arranged to be rendered inoperative, which may be done by removing its actuating rock-arm or by turning its rock-shaft so as to project said jaw toward the shaft of the carrier. (Shown in Fig. 17.) This carrier I is also provided, at points midway be-

tween the jaws 72 73, with swinging folding-blades 67 68, and between the said blade 68 and the jaw 73 with a third swinging folding-blade. These swinging folding-blades will be operated by suitable cams, as explained in said last-mentioned patent; but in this construction the folding-blade 94 will be arranged so as to be rendered inoperative, which may be done by removing its rock-arm or cam acting thereon. This carrier I is also provided with cutting-slots 57 58, the two latter of which are provided in blocks which are removable from said carrier, the latter, 75, being adapted to be inserted in the opening in which the jaw 73 operates, and the one 58 by being inserted in a suitable socket provided in the heads of the carrier. With this carrier I is arranged, preferably beneath it, a pair of rollers, 91 92, which may be geared to and driven by the toothed wheel 110 of said carrier, and at a suitable distance from it another pair of pulleys or rollers, 131 132, are arranged, around which rollers tapes 129 130 may be stretched, the tapes 129 either running around the carrier I and the roller or pulley 131 or around the roller 92 and said pulley or roller 131, and the tape 130 being stretched from the roller 91 to the roller or pulley 132 or around the roller 91, under the roller 92, and around the roller or pulley 132. If, now, we suppose the product emerging from the rollers 55 56 to be a full sheet's length, and it is desired to impart to it one transverse fold, the mechanisms will be arranged as in Fig. 17—that is, the cutters 53 54 and their pins will be removed from the carrier H and the block provided with a cutting-blade, 96, and pins will be substituted for the block carrying the creasing folding-blade 98, while the jaw 73 of the carrier I will be turned inward and rendered inoperative and the cutting-slot 75 adjusted in place. The swinging folding-blades 67, 68, and 94 will be rendered inoperative. As such sheet or web emerges from between the rollers 55 56 its leading end will be impaled by the pins near the cutter 96, which will carry said leading end around with the surface of the carrier H. As the central part or folding-line of the sheet overlying the creasing folding-blade 97 will be doubled thereby into the space provided by the jaw 72, which then stands open, the doubled edge thus formed will be nipped by said jaw, which closes thereon. Thus held by its doubled edge, the sheet will be carried around with the carrier I between its surface and the rollers 91 92, the end of one of its plies being stripped from the pins and the two plies laid together to complete the folding. The doubled edge is released by the opening movement of the jaw 72, accomplished in time to permit the folded sheet to be guided out between the tapes 129 130, or arranged as in Fig. 17. As the cutter 96 and cutting-slot 75 come into operation they will sever the web to detach the folded sheet and impale the leading end of the web upon the pins if the material is in the web form and entirely uncut. If it is in the web form and partially severed

transversely, the breaking-bar might supplant the said cutting-blade; if in the sheet form, the pins will simply engage the leading end of each sheet. If it is desired to impart a second transverse fold to the sheet, it may be accomplished by throwing into operation the vibrating folding-blade 94, in which case the block carrying the cutting-slot 58 must be removed and the tapes 129 130 stretched, as in Fig. 18. As the central part or folding-line of the once-folded sheet reaches the rollers 91 92 this blade 94 will be turned outward to double or fold said sheet into the nip of said rollers, which will then deliver it to the tapes 129 130, which will carry it out from between the rollers 131 132. If it is desired to fold the product of a half-sheet's length received from the rollers 55 56 with a single transverse fold, the creasing folding-blade 98 will be put in place of the cutter 96, and the cutters 76 77 and pins 53 54 will be placed in position in the carrier H. In the carrier I the block carrying the cutting-slot 75 will be removed and the jaw 73 restored to its operative condition. The folding-blades 67, 68, and 94 will remain inoperative, and the tapes 129 130 will be arranged as in Fig. 17. The material from the rollers 55 56 will be impaled upon the pins 53, carried around with the carrier H, be folded by the folding-blade 98 into the nip of the jaws 73, carried by the latter around with the carrier I, the doubled edge released and guided into the tapes 129 130, the forward ply being dragged from the pins 53. The next length of material will be impaled upon the pins 54, folded by the blade 97 and jaw 72 in like manner. If the material is in the web form, the cutters 76 77 will sever it into sheets; or if in the partially-severed form the breaker, taking the place of said cutter, will separate it into sheets; or if in the sheet form the pins 53 54 will engage it. If it is desired to impart an additional transverse fold to these folded half-sheets, the folding-blades 67 68 will be thrown into operation and the tapes 129 130 arranged as in Fig. 18, which sheets carried over the rollers 91 92 will be released in proper time by the jaws 72 73 to permit the same being folded by the blades 67 or 68 into the nip of said rollers, through which they will pass in a folded condition, and from which they will be delivered by said tapes, as before described; or, as is apparent, they may emerge directly from said rollers 91 92 for delivery in any common manner by a piling or other sheet-laying mechanism. The sheets, when once folded by the rollers 91 92, will be delivered between said rollers by a device like the fingers 5, herein-before described, when the tapes will be disengaged with.

A supplement web or sheets may be combined with the folded product of this apparatus in any of its forms. A convenient mode of introducing a supplement is by feeding such a printed supplement-web to the carriers E F or onto the guide G.

A peculiar mechanism for effecting the as-

sociation of one portion of printed web with another portion of the same web, and thus accomplish the introduction of a supplement sheet within the main sheet, forms the subject-matter of another application.

Devices differing from those herein referred to for operating the folding-blades also form the subject-matter of another application.

I do not abandon or dedicate to the public 10 any patentable features set forth herein and not hereinafter claimed, but reserve the right to claim the same either in a reissue of any patent that may be granted upon this application or in other applications for Letters Patent that I may make.

I therefore claim—

1. A longitudinal folding mechanism consisting of an internal guide and co-operating external turner, substantially as described.

2. A longitudinal folding mechanism consisting of an internal guide, co-operating external turner, and moving tapes, substantially as described.

3. A longitudinal folding mechanism consisting of an internal guide, external turner, and drawing rollers or cylinders, as H I, substantially as described.

4. The combination, with a printing mechanism, of a longitudinal folder consisting of an internal guide and co-operating external turner, whereby a web of paper is printed and longitudinally folded, all substantially as described.

5. The combination of a printing mechanism, a cutting mechanism, and a folding mechanism constructed of an internal guide and co-operating external turner and tapes, whereby a web of material is printed, severed transversely into sheets or short lengths, and folded longitudinally, all substantially as described.

6. The combination, with a printing mechanism, of a longitudinal folding mechanism consisting of an internal guide and co-operating external turner, a transverse cutting mechanism, and a transverse folding mechanism, all substantially as described.

7. The combination, with a longitudinal folding mechanism consisting of an internal guide and co-operating external turner, of moving tapes, all substantially as described.

8. The combination, with a printing mechanism, of a longitudinal folding mechanism consisting of an internal guide and co-operating external turner and moving tapes operating to carry the leading edge of the material through the folder, all substantially as described.

9. The combination, with a printing mechanism, and a longitudinal folding mechanism

consisting of an internal guide and co-operating 60 external turner and moving tapes, of a transverse cutting and folding mechanism, all substantially as described.

10. The combination, with a sheet gathering or collecting mechanism, of a longitudinal 65 folding mechanism consisting of a guide and co-operating turner, all substantially as described.

11. The combination, with a sheet gathering or collecting mechanism, of transverse and 70 longitudinal folding mechanisms, the latter consisting of a guide and co-operating turner, all substantially as described.

12. The combination, with a printing mechanism, of a delivery mechanism consisting of 75 carriers, as E F, provided with folding and gathering devices and with means for operating or suspending the action of the folding or gathering devices, or both, all substantially as described.

13. The combination, with printing mechanisms and web-cutting mechanisms, of a delivery mechanism consisting of carriers E F, provided with folding and gathering devices and with means for operating or suspending the 85 action of any or all of said cutting, folding, and gathering devices, all substantially as described.

14. The combination of a longitudinal folder consisting of turners, as described, with carriers, as E F, provided with cutting, folding, 90 and gathering devices, and with means for operating or suspending the action of any or all of said cutting, folding, and gathering devices, all substantially as described.

15. A mechanism consisting of two cylinders, as E F, carrying devices which 95 facilitate them to sever from a web of material, control, associate, and fold one or more sheets, as may be required for the desired signature, all substantially as described.

16. A carrier, as E, provided with members of a cutting device and two sets of pins for retaining the forward and rear ends of a sheet of paper, in combination with a coacting cutting 105 device, as F, substantially as described.

17. The combination of a printing mechanism, internal guide and external turner, and a slitter, as 133, operating to print, divide longitudinally, and associate the divided sections 110 together, substantially as described.

In testimony whereof I have hereunto set my hand in the presence of two subscribing witnesses.

LUTHER C. CROWELL.

Witnesses:

T. H. PALMER,
H. T. MUNSON.
